20 Claims. (Cl. 92—7)

This invention relates to improvements in method and apparatus for packing fibrous material in chemical pulp digesters.

One of the objects of the invention is to provide controllable means for evenly distributing chips or the like in a digester during the packing operation, so that the chips will be more densely and more uniformly packed than heretofore. Such packing permits me to improve the cooking efficiency, as it enables me to increase the output per cook and also the output per day, reduce chemicals and steam consumption, as well as improve the quality of the pulp and the yield of pulp per unit of raw material cooked.

Another object of the invention is to reduce the packing time and cost by the preliminary action of a fluid medium used in a first stage diffuser, followed by a final action of such a medium in a second stage diffuser. This two-stage method of diffusion results in more uniform distribution of the chips and increases the velocity of the same, so that a closer packing and more equal distribution is obtained. By the method, more chips can be evenly distributed and packed in a given digester space in considerably less time than with the methods heretofore used. Furthermore, as my chip packing device can be mounted on a truck, it is possible to use one chip packing apparatus for a large number of digesters without the necessity of providing a special track or trolley for the device. In addition, as I employ adjustable nozzles, I can vary the direction of the fluid medium jets so that the device may be employed with digesters of various sizes and shapes.

With the foregoing objects outlined and with other objects in view which will appear as the description proceeds, the invention consists in the novel features hereinafter described in detail, illustrated in the accompanying drawings, and more particularly pointed out in the appended claims.

In the drawings,

Fig. 1 is a vertical sectional view, partly in elevation, of one form of my apparatus shown attached to the neck of a digester.

Fig. 2 is an enlarged vertical section, partly in elevation, of the second stage diffuser of the apparatus.

Fig. 3 is a horizontal sectional view, taken on the line 3—3 of Fig. 2.

Fig. 4 is an elevation, partly in vertical section, of the first stage diffuser.

Fig. 5 is a horizontal sectional view, taken on the line 5—5 of Fig. 2.

Fig. 6 is a similar view on the line 6—6 of Fig. 4.

Referring to the drawings, 7 designates the upper end of a chemical pulp digester, and 8 designates the improved packer. Such packer may be readily mounted on a hand truck or the like, not shown. The packer preferably comprises an outer tube 9 designed to be introduced into the neck of the digester and provided with an external apertured flange 10 adapted to rest on the upper end of the digester. Projecting lugs 11 may be arranged on the tube so as to maintain the latter in spaced relation to the inner surface of the neck of the digester, whereby an annular passageway 12 is provided to permit the escape of air or the packing medium fluid.

A smaller inner tube 13 is centrifugally arranged in the tube 9, and may be supported by any suitable means, such as a spider 14. A pipe 15 for the packing fluid also aids in supporting the inner tube, and this pipe may be provided with a control valve 16.

An upper or first stage diffuser 17 is provided upon the inner tube, and it consists of a series of apertures 18 in the tube which are controlled by a damper ring 19 that has an operating handle 20 extending through a slot 21 in the larger tube. The damper ring, as best shown in Fig. 6, is provided with tangential nozzles 22 corresponding in number to the apertures 18. It will be obvious that the turning of the handle 20 will cause the damper ring 19 to move relatively to the tube 13, so that the volume of steam or the like discharged through the nozzles may be regulated.

The lower or second stage diffuser is designated 23, and it comprises a stationary hollow frusto cone 24 that is secured to and depends from the inner tube 13. A hollow rotatable shaft 25 extends through the inner tube, and is provided at its lower end with a rotatable ring 26 provided with a series of ports 27. These ports lead to pipes 28 which terminate in hollow universal or pivotal joints 29 that carry adjustable tangential nozzles 30. Each of these nozzles is pivotally connected by a link 31 to a vertically adjustable member 32, which in turn is connected to a rod 33 that may be moved up or down by any suitable means, such as a rack 33a and pinion 34 positioned within a housing 35 at the top of the inner tube. An operating shaft 36 carries the pinion and has a handle 37 for adjusting purposes. The hollow shaft may be driven by any suitable means, for example, by a rotatable shaft 38 and beveled gearing 39, the

latter being positioned within the housing 35. The shaft 38 may be driven by a motor, not shown. The shaft 38 rotates the shaft 25 in such a direction that the jets issuing from the nozzles 30 move in the opposite direction. Hence, the jets in striking the chips, will have a tendency to assist the shaft in rotating, this action being similar to that of a turbine.

In operation, chips or the like are introduced into the upper end of the tube 8, and as they fall through the tube, they are first acted upon by the jets of steam or the like issuing from the nozzles 22. These jets cause the chips to whirl, and the falling stream is organized into a whirling annulus. When the annulus of chips passes the second diffuser, the jets issuing from the nozzles of the latter not alone increase the whirling action, but transform the annulus into a hollow cone. By turning the handle 37, it will be recognized that the base of such cone may be increased or decreased, and consequently, the chips may be evenly distributed in the digester. In the past, chip packers had a tendency to pile the chips with the peak of the pile at the center of the digester. Consequently, the chips would be packed more densely along the vertical center of the digester than at other locations, and this obviously resulted in unequal packing. In accordance with my invention, the chips can be packed in flat layers, and the action of the diffusers is such as to not only pack the chips with great velocity, but to pack them more densely and uniformly.

After a digester has been packed, the apparatus may be readily lifted off the digester and transferred to another one.

While I have disclosed what I now consider to be a preferred embodiment of the apparatus in such manner that the construction of the same may be readily understood, it is manifest that my method may be practiced by other similar devices without departing from the spirit of the invention, as expressed in the claims.

What I claim and desire to secure by Letters Patent is:

1. A method of packing fibrous material in a digester or the like, comprising introducing a stream of fibrous material through a passageway into the upper end of the digester, discharging jets of fluid outwardly from the axis of said passageway into said stream and thereby organizing the stream into a whirling annular mass, and afterwards discharging other jets of fluid outwardly from said axis into the mass and thereby causing the mass to assume a substantially conical form while falling into the digester.

2. A method of packing fibrous material in a digester or the like, comprising introducing a stream of fibrous material into the upper end of the digester, discharging jets of fluid into said stream and thereby organizing the stream into a whirling annular mass, afterwards introducing other jets of fluid into the mass and thereby causing the mass to assume a substantially conical form while falling into the digester, and adjusting the last mentioned jets to vary the diameter of the base of the cone-shaped mass.

3. A method of packing wood chips or the like, comprising feeding a stream of falling chips through a passageway into the upper end of a digester, organizing said stream into an annular whirling mass by discharging jets of fluid outwardly from the axis of the passageway into said stream, and afterwards introducing other jets of fluid into the annular whirling mass and

thereby continuing the whirling of the mass and transforming the same into a hollow cone.

4. A method of packing wood chips or the like, comprising feeding a stream of falling chips into the upper end of a digester, organizing said stream into an annular whirling mass, afterwards continuing the whirling of the mass and transforming the same into a hollow cone, and controllably varying the diameter of the base of the cone. 10

5. A chip packing apparatus comprising a conduit through which chips are introduced into a digester, a first stage diffuser in the conduit provided with tangential nozzles for introducing jets of a packing fluid into the chips, and a second stage diffuser positioned below the first diffuser and provided with tangential nozzles for directing other jets of the packing fluid into the chips. 15

6. A chip packing apparatus comprising a conduit through which chips are introduced into a digester, a first stage diffuser in the conduit provided with tangential nozzles for introducing jets of a packing fluid into the chips, a second stage diffuser positioned below the first diffuser and provided with tangential nozzles for directing other jets of the packing fluid into the chips, said first stage diffuser comprising a tube for conveying the packing fluid, a series of ports in the tube, a damper ring movably mounted on the tube, said first mentioned tangential nozzles 20 being carried by said ring, and means for moving the ring to regulate the volume of fluid flowing through the ports to said first mentioned tangential nozzles. 25

7. A chip packing apparatus comprising a conduit through which chips are introduced into a digester, a first stage diffuser in the conduit provided with tangential nozzles for introducing jets of a packing fluid into the chips, a second stage diffuser positioned below the first diffuser and provided with tangential nozzles for directing other jets of the packing fluid into the chips, and means for rotating the nozzles of the second stage diffuser. 30

8. A chip packing apparatus comprising a conduit through which chips are introduced into a digester, a first stage diffuser in the conduit provided with tangential nozzles for introducing jets of a packing fluid into the chips, a second stage diffuser positioned below the first diffuser and provided with tangential nozzles for directing other jets of the packing fluid into the chips, said second stage diffuser comprising hollow universal joints carrying the nozzles of the second stage diffuser, and means for radially adjusting the nozzles of the second stage diffuser to cause their outlet ends to approach or move away from the axis of said conduit. 45

9. A chip packing apparatus comprising a conduit through which chips are introduced into a digester, a first stage diffuser in the conduit provided with tangential nozzles for introducing jets of a packing fluid into the chips, a second stage diffuser positioned below the first diffuser and provided with tangential nozzles for directing other jets of the packing fluid into the chips, said second stage diffuser comprising a tube for conducting the packing fluid, an apertured rotatable ring receiving the fluid from the tube, hollow pivotal joints to receive the fluid from the ring, the nozzles of the second stage diffuser being carried by said joints, means for rotating said ring, and means for swinging said nozzles outwardly or inwardly relatively to the axis of said tube. 60 65 70

10. A chip packing apparatus comprising a conduit through which chips are introduced into a digester, a first stage diffuser in the conduit provided with tangential nozzles for introducing jets of a packing fluid into the chips, a second stage diffuser positioned below the first diffuser and provided with tangential nozzles for directing other jets of the packing fluid into the chips, means for rotating the nozzles of the second stage diffuser, and means for adjusting the nozzles of the second stage diffuser to cause their outlet ends to approach or move away from the axis of said conduit.

11. An apparatus of the character described, comprising inner and outer tubes, means for spacing the tubes from one another to provide a chip passageway between the same, means for introducing a packing fluid into the inner tube, a first stage diffuser mounted on the tube and provided with tangential nozzles for discharging jets of fluid from the tube into said passageway, a rotatable shaft extending through the inner tube and carrying a series of pivotally mounted nozzles at its lower end to provide a second stage diffuser, and means for adjusting said nozzles to cause their outlet ends to approach or move away from the axis of said shaft.

12. An apparatus of the character described, comprising inner and outer tubes, means for spacing the tubes from one another to provide a chip passageway between the same, means for introducing a packing fluid into the inner tube, a first stage diffuser mounted on the tube and provided with tangential nozzles for discharging jets of fluid from the tube into said passageway, a rotatable shaft extending through the inner tube and carrying a series of pivotally mounted nozzles at its lower end to provide a second stage diffuser, means for adjusting said nozzles to cause their outlet ends to approach or move away from the axis of said shaft, the last mentioned means comprising a vertically adjustable member, links pivotally connecting said member to the last mentioned nozzles, and a rod extending through the shaft and operatively connected to said member.

13. An apparatus of the character described, comprising inner and outer tubes, means for spacing the tubes from one another to provide a chip passageway between the same, means for introducing a packing fluid into the inner tube, a first stage diffuser mounted on the tube and provided with tangential nozzles for discharging jets of fluid from the tube into said passageway, a rotatable shaft extending through the inner tube and carrying a series of pivotally mounted nozzles at its lower end to provide a second stage diffuser, means for adjusting said nozzles to cause their outlet ends to approach or move away from the axis of said shaft, the last mentioned means comprising a vertically adjustable member, links pivotally connecting said member to the last mentioned nozzles, a rod extending through the shaft and operatively connected to said member, and means for vertically adjusting said rod.

14. An apparatus of the character described, comprising inner and outer tubes, means for spacing the tubes from one another to provide a chip passageway between the same, means for introducing a packing fluid into the inner tube, a first stage diffuser mounted on the tube and provided with tangential nozzles for discharging jets of fluid from the tube into said passageway, a rotatable shaft extending through the inner tube and carrying a series of pivotally mounted nozzles

at its lower end to provide a second stage diffuser, means for adjusting said nozzles to cause their outlet ends to approach or move away from the axis of said shaft, and a hollow frusto cone positioned at the lower end of the inner tube and surrounding the nozzles of the second stage diffuser.

15. A portable chip packer adapted to be employed with a number of digesters, comprising an outer tube, means for supporting the tube on the upper end of a digester in such manner that fluid may escape upwardly between the tube and the neck of the digester, an inner tube concentrically and rigidly arranged within the outer tube, a conduit for introducing a packing fluid into the inner tube, an upper first stage diffuser mounted on the inner tube and provided with a series of tangential nozzles which receive fluid from the inner tube, a hollow frusto cone secured to the lower end of the inner tube, an apertured ring rotatably mounted in said cone, a hollow shaft extending through the inner tube and carrying said ring, nozzles pivotally secured to said ring and having outlet ends adapted to be moved toward or away from the axis of said shaft, and a vertically adjustable rod extending through the hollow shaft and operatively connected to the last mentioned nozzles.

16. A portable chip packer adapted to be employed with a number of digesters, comprising an outer tube, means for supporting the tube on the upper end of a digester in such manner that fluid may escape upwardly between the tube and the neck of the digester, an inner tube concentrically and rigidly arranged within the outer tube, a conduit for introducing a packing fluid into the inner tube, an upper first stage diffuser mounted on the inner tube and provided with a series of tangential nozzles which receive fluid from the inner tube, a hollow frusto cone secured to the lower end of the inner tube, an apertured ring rotatably mounted in said cone, a hollow shaft extending through the inner tube and carrying said ring, nozzles pivotally secured to said ring and having outlet ends adapted to be moved toward or away from the axis of said shaft, a vertically adjustable rod extending through the hollow shaft and operatively connected to the last mentioned nozzles, a housing arranged at the upper end of the inner tube, and means in said housing for rotating said shaft.

17. A portable chip packer adapted to be employed with a number of digesters, comprising an outer tube, means for supporting the tube on the upper end of a digester in such manner that fluid may escape upwardly between the tube and the neck of the digester, an inner tube concentrically and rigidly arranged within the outer tube, a conduit for introducing a packing fluid into the inner tube, an upper first stage diffuser mounted on the inner tube and provided with a series of tangential nozzles which receive fluid from the inner tube, a hollow frusto cone secured to the lower end of the inner tube, an apertured ring rotatably mounted in said cone, a hollow shaft extending through the inner tube and carrying said ring, nozzles pivotally secured to said ring and having outlet ends adapted to be moved toward or away from the axis of said shaft, a vertically adjustable rod extending through the hollow shaft and operatively connected to the last mentioned nozzles, a housing arranged at the upper end of the inner tube, and means in said housing for adjusting said rod.

18. A portable chip packer adapted to be em-

ployed with a number of digesters, comprising an outer tube, means for supporting the tube on the upper end of a digester in such manner that fluid may escape upwardly between the tube and 5 the neck of the digester, an inner tube concentrically and rigidly arranged within the outer tube, a conduit for introducing a packing fluid into the inner tube, an upper first stage diffuser mounted on the inner tube and provided with a 10 series of tangential nozzles which receive fluid from the inner tube, a hollow frusto-cone secured to the lower end of the inner tube, an apertured ring rotatably mounted in said cone, a hollow shaft extending through the inner tube and carrying said ring, nozzles pivotally secured to said ring and having outlet ends adapted to be moved toward or away from the axis of said shaft, a vertically adjustable rod extending through the hollow shaft and operatively connected to the last 15 mentioned nozzles, and means for simultaneously adjusting the nozzles of the first stage diffuser circumferentially relatively to the inner tube for varying the volume of packing fluid issuing from the nozzles of the first stage diffuser. 20

19. A chip packing apparatus comprising a conduit through which chips are introduced into a digester, a first stage diffuser in the conduit provided with nozzles for introducing jets of a packing fluid into the chips, and a second stage diffuser positioned below the first diffuser and provided with nozzles for directing other jets of the packing fluid into the chips, all of said nozzles projecting outwardly from the axis of said conduit. 5 10

20. A chip packing apparatus comprising a substantially cylindrical conduit through which chips are introduced into a digester, a first stage diffuser in the conduit provided with nozzles for introducing jets of a packing fluid into the chips, and a second stage diffuser positioned below the first diffuser and provided with nozzles for directing other jets of packing fluid into the chips, all of said nozzles projecting outwardly from the axis of said conduit and having their extremities arranged tangentially to the wall of the conduit. 15 20
